UNITED STATES PATENT OFFICE

2,479,715

COASTER TOY

Dewey Benlon, Kansas City, Mo.

Application October 18, 1946, Serial No. 704,202

2 Claims. (Cl. 104—53)

1

The present invention relates to a coaster toy adapted for use by children and more particularly to an inclined track for use in conjunction with a mobile vehicle adapted to be ridden by a child.

A particular object of the invention is to provide a track which is capable of being easily adjusted for positioning either end thereof in an elevated position so that the mobile vehicle may be ridden in both directions relatively to the track and so that after the vehicle has been propelled by gravity from one end to the opposite, lower end, said last mentioned end of the track may be elevated for depressing the first mentioned end and so that the vehicle may then be propelled by gravity in the opposite direction.

Various other objects and advantages of the invention will hereinafter become more fully apparent from the following description of the drawings, illustrating a preferred embodiment thereof, and wherein:

Figure 1 is a side elevational view, partly broken away and illustrating a preferred embodiment of the coaster toy in an operative position;

Figure 2 is an end elevational view of the same looking toward the right-hand end of Figure 1;

Figure 3 is a fragmentary top plan view of the track and base with the mobile vehicle removed therefrom;

Figure 4 is a top plan view of the base, with the track removed;

Figure 5 is an enlarged longitudinal, substantially central sectional view through the mobile vehicle or wheeled truck and showing the vehicle in an applied position;

Figure 6 is a bottom plan view thereof;

Figure 7 is a cross sectional view of the truck and track taken substantially along a plane as indicated by the line 7—7 of Figure 5;

Figure 8 is a fragmentary longitudinal sectional view of a portion of the track and showing a portion of one of the wheels of the truck disposed in a recess thereof, and

Figure 9 is a fragmentary bottom plan view of a part of the track and with an end cleat removed therefrom.

Referring more specifically to the drawings, the toy coaster in its entirety is designated generally 10 and includes a wheeled vehicle or truck, designated generally 11, a track for the wheeled vehicle or truck, designated generally 12, and a base for supporting the track, designated generally 13.

The base 13 includes a pair of corresponding blocks or end members 14 which are located at the ends of the base 13 and which are connected by a longitudinal beam 15. The ends of the beam 15 seat in upwardly opening recesses 16 of the blocks 14 and are secured therein by fastenings 17, as best seen in Figure 4. A pair of bars 18 are secured to the upper side of each block 14

2

and parallel to the beam 15 and on either side thereof, as best illustrated in Figures 2 and 4.

The track, designated generally 12, includes a pair of laterally spaced substantially parallel bars 19 which are disposed in substantially the same plane and which are connected at their complementary ends by transverse cleats 20, which are secured to the under sides of the bars 19 by fastenings 21 and which retain the bars 19 in laterally spaced apart relationship so that the adjacent longitudinal edges of said bars will combine to form a slot 22 therebetween and which extends longitudinally of the track 12. A relatively thick strip of cushioning material such as rubber, designated 23, is secured along the inner longitudinal edge of each cleat 20 and is accordingly disposed transversely of the track 12 and with the intermediate portions of each strip 23 disposed just beneath and transversely of the slot 22.

20 A rod or pin 24 extends longitudinally through each cleat 20 and beyond the ends thereof. A pair of rigid links 25 are connected to each rod 24. Said links 25 are pivotally mounted at corresponding ends thereof on the rod 24 between the ends of the cleat 20 and the side edges of the track 12 and the headed outer ends of the rod 24. The opposite ends of the links 25 are pivotally connected to the exposed ends of a rod or pin 26 which extends longitudinally through the block 14 of the end of the base 13 and which is adjacent to the aforementioned cleat 20. It will thus be readily apparent that each end of the track 12 is swingably connected to the complementary end of the base 13 by a pair of the rigid links 25 and a rod or pin 24 and 26.

As clearly illustrated in Figure 1, the track 12 is of a length greater than the length of the base 13 so that when one pair of links 25 is in an upright position, as seen at the right-hand end of Figure 1, the other pair of links 25 will be in substantially a horizontal position and extending beyond the opposite end of the base 13, for supporting the opposite, left-hand end of the track 12 in a depressed position. Each pair of the links 25 is connected by a cross bar 27 which is secured to the outer edges thereof and which is disposed to engage a supporting surface on which the blocks 14 are resting when the links 25 thereof are in substantially a horizontal position, as illustrated in the left-hand end of Figure 1. The bars 19 of the track 12 are preferably provided with brace strips 28 which are secured to the under sides thereof and adjacent their outer edges and which extend to adjacent the cushioning abutment members 23. Said brace strips 28 have portions which rest on the strips 18 of the base 13 when an end of the track 12 is in its normal, depressed position, as illustrated in 45 dotted lines at the left-hand end of Figure 1.

The wheeled vehicle or truck 11 comprises a platform 29 which is provided with cleats 30 which are secured to the under side thereof and transversely and at the end of the platform 29 and to which are secured pairs of depending forks 31, as best seen in Figure 7. Each end cleat 30 is provided with two pairs of depending forks 31, including a pair of forks arranged above each of the track rails or bars 19 and a roller 32 is journaled between the forks of each pair of forks 31 and on an axle 33, the ends of which are anchored in the forks, so that the vehicle 11 is provided at each end thereof with a wheel engaging each of the bars or rails 19.

A supporting brace 34 is disposed longitudinally beneath the platform 29 and secured at its ends to the intermediate portions of the undersides of the cleats 30 and is provided, intermediate of its ends, with a depending flange or web 35 which extends downwardly into the slot 22 and which is provided with an opening 36, adjacent its bottom free edge. A retaining bar 37 is secured longitudinally against the bottom edge of the flange 35 by means of a bolt 38 which extends through washers 39 and 40, through the bar 37 and the bottom edge portion of the flange 35 into the opening 36 and which is provided with a nut 41 on its threaded shank end and which is disposed in the opening 36, and by means of which the bar 37 is secured to the flange 35. The brace 34 is preferably formed of metal and the washer 39, which is cup-shaped, is preferably formed of rubber to provide a shock absorbing means in case said parts strike a part of the base during movement of the truck 11 on the track 12.

The ends of the bar 37 extend to substantially beyond the ends of the flange 35 to receive the lower ends of a pair of rods 42. The rods 42 each have a portion which extends through the longitudinal brace 34 and an opposite, upper end portion 43 which is lapped and thereby anchored between the platform 29 and the brace 34. Each rod 42 is also provided with a lapped portion 44, intermediate of the brace 34 and bar 37 and between which and said bar 37 a roller 45 is journaled on the rod 42. The roller 45 is thus journaled on each rod 42, as seen in Figure 5, between the bar 37 and the lapped portion 44, so that the two longitudinally spaced rollers 45 are positioned to move in the slot 22 for engaging the inner edges of the rails or bars 19 for guiding the truck, during its movement from end to end of the track 12. The washer or disk 40 is of a diameter substantially greater than the width of the slot 22 and accordingly functions to prevent disengagement of the truck 11 from the track 12 and disengagement of the rollers 45 from the slot 22.

Assuming that the coaster toy is assembled and disposed as seen in Figure 1, the truck or vehicle 11 will be retained at the upper end of the track 12 by reason of the fact that the rails 19 are provided with recesses 46 adjacent each end thereof to receive the rear or uppermost rollers 32 and to thus provide a wheel lock which will prevent the truck from coasting down the inclined track 12 until the rider has seated himself upon the platform 29 and has manually moved the rear wheels 32 out of engagement with the recesses 46. It will be readily apparent that the truck 11 will then roll on the rails 19 to the lower end of the track 12 at which time the forward end of the bar 37 will strike the resilient

abutment strip 23 for stopping the forward progress of the vehicle 11. The child may then lift the lower end of the track 12, and at which the vehicle 11 is located, for swinging said end on the links 25 to an elevated position and with the links 25 disposed substantially perpendicular or in a position to correspond to the position of the links 25 at the right-hand end of Figure 1. Likewise, this will cause the right-hand end of the track 12, as seen in Figure 1, to swing downwardly and to the right to assume a position corresponding to the left-hand end of the track 12, as seen in Figure 1. The child may then ride the truck 11 in the opposite direction and in the same manner as previously described.

The rails or bars 19 are made identical on both sides so that should one side of the rails 19 become worn, the cleats 20 and abutments 23 can be removed and applied to the opposite side thereof after which the rails can be inverted. For this reason, the ends of both sides of the rails 19 are provided with the recesses 46, as indicated by the fragmentary bottom plan view of corresponding ends of the rails 19, as illustrated in Figure 9.

The track 12 and base 13 may be made in various length and various other modifications and changes are contemplated and may obviously be resorted to, without departing from the spirit and scope of the invention as hereinafter defined by the appended claims.

I claim:

1. In an inclined runway for toy wheeled vehicles or the like, a rigid base, a rigid track disposed over the base, rigid link means swingably connecting the ends of the track to the complementary ends of the base, said track being longer than the base whereby when one end of the track is disposed in an elevated position over the complementary end of the base, the opposite end of the track will be in a lowered position with respect to said first mentioned end and disposed beyond the opposite end of the base, and a gravity propelled vehicle mounted for movement in either direction on said track.

2. In an inclined runway for toy wheeled vehicles or the like, an elongated rigid base, a rigid link pivotally connected at an end thereof to each end of the base, and a rigid track disposed over the base of a length in excess of the length of said base, said track being pivotally connected at its ends to the opposite, free ends of said rigid links, whereby either end of the track may be disposed in an elevated position directly over the complementary end of the base and with the link, associated therewith, disposed in substantially an upright position and for positioning the opposite end of the track beyond and in engagement with the opposite end of the base and at a lower level.

DEWEY BENLON.
